DEEP DRILLING MACHINE

Roger G. Cudini, Birmingham, Mich., assignor to
 Moynahan Bronze Co., Detroit, Mich., a corporation of Michigan

Application May 28, 1948, Serial No. 29,690

13 Claims. (Cl. 77—5)

1

The present invention relates to an improved drilling machine and, more particularly, to an improved machine for accurately drilling holes with an elongated drill through a plurality of spaced projecting portions on a workpiece such as a hinge or connector part, or the like.

It is an object of the invention to provide an improved drilling machine for accurately drilling apertures through a plurality of spaced projecting portions of an elongated workpiece thereby insuring proper cooperation between complementary mating workpieces.

A further object of the invention is to provide an improved drilling machine for drilling holes in spaced projecting portions of a workpiece of considerable length, which machine provides a minimum bearing surface engaging the drill.

Another object of the invention is to provide an improved drilling machine adapted for drilling a hole through a plurality of spaced projecting portions of a workpiece and including retractable drill positioning members movable with the drill and adapted to project between projecting portions of the workpiece to engage and support the drill adjacent its cutting end during the entry of the cutting end into each of the projecting portions of the workpiece.

It is also an object of the invention to provide a drilling machine incorporating improved means for supporting an elongated drill during a drilling operation.

It is also an object of the present invention to provide an improved drilling machine of the above type adapted for drilling a hole through a plurality of spaced projecting portions on a workpiece, which projecting portions are disposed along a general or gradual curve.

Other objects of the invention will become apparent from a consideration of the following specification, the appended claims and the accompanying drawings wherein:

Figure 1 is a broken view in elevation of a drilling machine embodying the invention;

Fig. 2 is a broken plan view of the construction illustrated in Fig. 1;

Fig. 3 is a broken enlarged sectional view of the construction illustrated in Fig. 1 taken substantially along the line 3—3 thereof;

Fig. 4 is an enlarged fragmentary sectional view of the construction illustrated in Fig. 3 taken substantially along the line 4—4 thereof;

Fig. 5 is a fragmentary sectional view of the construction illustrated in Fig. 4 taken along the line 5—5 thereof;

2

Fig. 6 is a broken enlarged sectional view of the construction illustrated in Fig. 2 taken substantially along the line 6—6 thereof;

Fig. 7 is a broken plan view illustrating the relative position of the parts after the drill has advanced partially through the workpiece.

Fig. 8 is a broken elevational view of a modified embodiment of the invention;

Fig. 9 is a broken plan view, having parts broken away, of the construction illustrated in Fig. 8; and

Fig. 10 is a broken enlarged sectional view of the construction illustrated in Fig. 9 taken substantially along the line 10—10 thereof.

15 In general, the present invention is directed to a machine for drilling holes through a plurality of spaced projecting portions of an elongated workpiece. From a complete understanding of the present invention, it will be appreciated that the improvements thereof, while not so specifically limited, have particular utility in the drilling of pintle holes in hinge or connector parts. It will be appreciated that in the construction of mating hinge parts it is important that all of the pintle holes throughout the lengths of the mating hinge parts are maintained concentric to insure that the hinge parts will properly mate. Similarly, in mating connector parts, the spaced projecting portions of which

20 are disposed along a curve, it is likewise important that the holes be accurately located in order that the connector parts will properly mate and receive the connecting pin or rod.

25 Referring to the drawings, and more particularly, to Figs. 1-7 inclusive, the drilling machine 20 there illustrated is adapted for drilling a workpiece 22 having a plurality of aligned projecting portions 24 disposed along its length. The illustrated workpiece 22 is an elongated hinge

30 part having equally spaced projecting portions 24 adapted to receive therebetween similar projecting portions of a complementary mating hinge member. The machine 20 of the present invention is adapted to drill longitudinally through the hinge 22 to provide a pintle opening 26 in each of the projecting portions 24.

35 The drilling machine 20 generally comprises a base 28 mounted on suitable supporting legs 30 and carrying a workpiece support generally indicated at 32 and a carriage generally indicated at 34 mounted on the base 28 for sliding movement longitudinally thereof for moving a drill 36 carried by the carriage 34 to and from

40 and through the workpiece 22.

45

The drilling machine 20 generally comprises a base 28 mounted on suitable supporting legs 30 and carrying a workpiece support generally indicated at 32 and a carriage generally indicated at 34 mounted on the base 28 for sliding movement longitudinally thereof for moving a drill 36 carried by the carriage 34 to and from

50 and through the workpiece 22.

55 The work support 32 generally comprises a

plate 33 disposed centrally of and extending longitudinally of the base 28 adjacent the left-hand end thereof as viewed in Figs. 1 and 2, and secured to the base 28 by a plurality of screws 40. An elongated workpiece supporting block 42 is disposed centrally of and extends longitudinally of the plate 33 and is secured thereto by screws 44 extending upwardly through the plate 33 and threading into the block 42. The upper surface of the workpiece supporting block 42 is formed to provide a plurality of longitudinally spaced upwardly extending projections 46 having accurately aligned V-shaped surfaces 48 individual to and adapted to engage and support the spaced projecting portions 24 formed on the workpiece 22. The workpiece 22 is securely held in the position illustrated with the projecting portions 24 seated on the V-shaped surfaces 48 of the block 42 and the leaf portion 50 of the workpiece extending vertically upwardly, by a plurality of screw-operated clamps 52 mounted above the block 42 on a beam member 54 mounted on and extending longitudinally of the base 28.

The carriage 34 comprises a motor carrying portion 56 which is mounted in a centrally disposed longitudinally extending groove or slide 58 formed in the base 28. The carriage portion 56 mounts a drill chuck 60 adapted to receive and rotate the elongated drill 36, and a motor 62 which drives the drill chuck 60 through any suitable means such as the wheel and belt assembly indicated at 64. The carriage 34 also includes portions 66 and 68 disposed adjacent the leading or cutting end of the drill 36 and which support means generally indicated at 70 for accurately positioning the cutting end of the drill 36 during the drilling operation. The carriage portions 66 and 68 are adapted to slide along parallel ways 72 and 74 extending longitudinally of the base 28 on opposite sides of the centrally disposed groove 58. These carriage portions 66 and 68 are connected to the motor carrying carriage portion 56 by means of rods 76 and 78.

In the preferred embodiment illustrated, movement of the carriage 34 longitudinally of the base 28 to move the drill 36 to and from and through the workpiece 22, is effected by means of a hydraulic cylinder and piston motor 80. Fluid under pressure is supplied to the motor 80 from a tank 82 through a suitable conventional hydraulic valve generally indicated at 84 by a pump 86 driven by a motor 88.

The present invention also contemplates the provision of means generally indicated at 90 for supporting the elongated drill 36 at a plurality of points intermediate the drill chuck 60 and the workpiece 22. For this purpose, a plurality of pairs of opposed drill supporting elements 92 and 94 are provided, which are mounted on individual supporting plates 96 and 98 fixed to plate members 100 and 102 which extend longitudinally of and are secured to the base 28 at opposite sides of the central groove or slide 58. As best illustrated in Figs. 6 and 7, the plates 96 and 98 are provided with bearing blocks 104 which slidably mount the elements 92 and 94 for movement transversely of and toward and away from the drill 36. These elements 92 and 94 are yieldably held in the position illustrated in Fig. 6 by coil springs 106 surrounding the elements 92 and 94 between the bearing blocks 104 and engaging the outer of these bearing blocks at their outer ends and engaging collars 108 fixed to the drill supporting elements at their

inner ends. The collars 108 carry an upwardly projecting arm 110 mounting a roller 112 on its upper end adapted to be engaged by cam plates 114 mounted on the motor supporting portion 56 of the carriage 34 to move the drill supporting elements 92 and 94 upwardly, as illustrated in Fig. 7, as the carriage moves along the base 28.

At their inner ends, the elements 92 and 94 carry drill engaging jaws 116 and 118 respectively. These jaws are provided with V-shaped surfaces 120 and 122 respectively adapted to engage and support the drill 36, the jaw 116 being bifurcated, as best illustrated in Figs. 2 and 7, to receive the jaw element 116 and permit the V-shaped surfaces 120 and 122 of both jaw elements to cooperate in supporting the drill 36.

It will now be appreciated that, when the carriage is in the fully retracted position illustrated in Figs. 1 and 2, the jaws 116 and 118 of each pair of drill supporting elements 92 and 94 are in position to support the drill 36 thereby providing support for the drill 36 at a plurality of points spaced along its length. It will also be appreciated that, as each pair of drill supporting elements 92 and 94 is approached by the motor carrying portion 56 of the carriage 34, the cam plates 114 mounted on the motor carrying portion 56 engage the rollers 112 to move the elements 92 and 94 outwardly and disengage the jaws 116 and 118 from the drill 36 and move them out of the path of the motor carrying portion 56 as it advances along the central groove 58 of the base 28 during the drilling operation. It will also be noted that the cam plates 114 permit the jaws 116 and 118 to close after passage of the cam plates 114 which also are similarly shaped at both ends. During the return movement of the carriage 34, the drill supporting elements 92 and 94 are similarly retracted to move the jaws 116 and 118 from the path of the carriage. As the cam plates 114 pass to the right, as viewed in Figs. 2 and 7, during the return movement of the carriage 34 the drill supporting elements 92 and 94 are then permitted to be moved inwardly so that the jaws 116 and 118 on their inner ends again engage and support the drill 36.

The above mentioned drill positioning means 70 mounted on the carriage portions 66 and 68 is best illustrated in Figs. 3, 4 and 5 and comprises a pair of opposed drill supporting members 130 and 132 disposed transversely of the base 28 and slidably mounted in housings 134 and 136 respectively for movement toward and away from each other. The adjacent end surfaces of the members 130 and 132 are grooved as indicated at 138 in Fig. 4 for engaging and supporting the drill 36. In spaced relation to their inner ends, the members 130 and 132 carry collars 140 and 142 respectively secured thereto for movement therewith and disposed to engage the opposite lateral faces of the work supporting block 42 as the adjacent end faces of the members 130 and 132 move into engagement. The members 130 and 132 are held against rotating, so that the grooves 138 will at all times be properly disposed for engaging the drill 36, by pins 143 mounted on the collars 140 and 142 eccentrically of the members 130 and 132 and projecting through closely fitting apertures in the housings 134 and 136.

The drill supporting members 130 and 132 are yieldably held in the position illustrated in the drawings by spring means disposed within the housings 134 and 136 and comprising a collar 144 secured to the drill positioning member and a coil

spring 146 surrounding the drill positioning member and engaging the housing at its outer end and the collar 144 at its inner end.

It will be appreciated that the drill positioning members 130 and 132 move longitudinally of the base 28 with the carriage 34 and, accordingly, means are provided for withdrawing the drill positioning members 130 and 132 from engagement with the drill 36 to prevent their engaging and becoming jammed against the projecting portions 24 of the workpiece 22 through which the drill 36 passes. This means is similar for both of the drill positioning members 130 and 132 and comprises conventional solenoid means generally indicated at 148 individual to the members 130 and 132 adapted to move the associated drill positioning member outwardly against the action of the spring 146.

To provide for the automatic withdrawing of the work positioning members 130 and 132 during the desired portions of the drilling operation, the solenoids 148 are connected to a suitable electric switch 150 mounted on the base 28 and having a cam follower arm 152 adapted to actuate the switch and which is resiliently urged against a cam plate 154 mounted on the carriage connecting rod 78. It will be appreciated that the shape of the cam plate 154 will correspond to the dimensions and spacing of the projecting portions 24 of the workpiece 22, the cam plate 154 being so shaped that the members 130 and 132 are permitted to engage and position the drill 36 during the entry of the drill into each of the projecting portions 24, and to be withdrawn after the drill is started in each of said projecting portions 24 and before the members 130 and 132 are moved into interfering engagement with the projection portions 24 of the workpiece.

It will be appreciated that, as best illustrated in Fig. 4, the flutes of the drill preferably extend back from the leading or cutting end of the drill for only a short distance thereby reducing the tendency of the drill to increase the size or alter the shape of the holes in the projecting portions 24 through which the cutting edge of the drill has passed.

It will be appreciated that a suitable cutting fluid or coolant is preferably applied to the drill 36 and the workpiece 22 by any suitable means (not shown).

The modified embodiment of the invention illustrated in Figs. 8, 9 and 10 is a drilling machine generally indicated at 160 and adapted for drilling a connector part 162 having a plurality of spaced projecting portions 164 disposed along a gentle or gradual curve, as best illustrated in Fig. 9. The drilling machine 160 is in many respects similar to the drilling machine 20 above described, but is provided with a work support generally indicated at 166 differing from the work support 22 of the machine 20, as hereinafter described. The machine 160 further differs from the above described machine 20 in that it contains no carriage portion corresponding to the carriage portion 66 of the machine 20, and in that the carriage portion 168, corresponding to the carriage portion 68 of the machine 20, carrier drill positioning means generally indicated at 170 and differing from the above described drill positioning means 70 as indicated in detail hereinafter.

The work support 166 comprises a work supporting plate 172 extending longitudinally of the base 174 and fixed to a way or slide 176 thereof, corresponding to the way 72 of the above described machine 20. The workpiece 162 is sup-

ported upon the plate 172 on a plurality of blocks 178 which rest upon the plate 172 and receive the downwardly extending projecting portions 164 of the connecting part 162. The workpiece 162 is supported so that the projecting portions 164 are disposed along a gentle or gradual curve lying in a plane parallel to the plane of the supporting plate 172. The edge of the plate 172 presenting toward the carriage portion 168 is formed to provide a cam or guide surface 180 which is disposed along a similar gradual or gentle curve parallel to the curve along which the workpiece projecting portions 162 are disposed. The workpiece 162 is securely clamped down against the blocks 178 by screw-operated clamps 182 which engage an upwardly projecting flange 184 of the workpiece and are mounted along a bar 186 extending longitudinally of and mounted on the base 174 and corresponding to the member 54 of the above described machine 20.

In the machine 160 the drill positioning means 170 comprises a C-shaped connecting member 188 disposed to straddle the bar 186 and the workpiece 162 during movement of the carriage longitudinally of the base 174 as during a drilling operation. At its opposite ends, the C-shaped member 188 terminates in horizontally outwardly extending plate portions 190 and 192 which are secured to bearing blocks 194 and 196 disposed on opposite sides of the workpiece 162 by screws 198. To prevent relative movement of the blocks 194 and 196, the C-shaped member 188 of the construction illustrated is T-shaped in cross section. Opposed drill positioning members 200 and 202 are disposed transversely of the base 174 and slidably mounted in the blocks 194 and 196 respectively for movement toward and away from the drill. At their inner adjacent ends, the drill positioning members 200 and 202 carry jaw elements 204 and 206 respectively the adjacent end faces of which are adapted to engage the drill to accurately position it during its entry into each of the projecting portions 164 of the connector part 162. The members 200 and 202 and, consequently, the jaws 204 and 206 carried thereby, are urged inwardly and yieldably held in the position illustrated in Fig. 10, in which the jaws engage and position the drill, by springs 208 and 210 which are disposed within the blocks 194 and 196 respectively and engage outwardly presenting shoulders on the drill positioning members 200 and 202.

As in the above described machine 20 the drill positioning members 200 and 202 are moved outwardly against the action of the springs 208 and 210, to prevent interference between the jaws 204 and 206 and the projecting portions 164 of the workpiece 162 during movement of the carriage along the base 174, by solenoids 212 and 214 which are suitably mounted on the outwardly extending plate portions 190 and 192 of the C-shaped member 188. The shape of the drill positioning members 200 and 202 outwardly of their engagement with the springs 208 and 210, and their sliding engagement with the blocks 194 and 196 is such as to prevent rotation of the members 200 and 202 in the blocks 194 and 196 and, accordingly, insure that the jaw elements 204 and 206 which are fixed in the outer ends of the drill positioning members 200 and 202 will, at all times, be disposed in the proper rotative position for engaging the drill.

It will be appreciated that during the drilling of the workpiece 162 the drill positioning means 170 must follow the curve along which the work

projecting portions 164 of the workpiece are disposed. Accordingly, the machine 160 includes means mounting the entire drill positioning assembly 170 for movement transversely of the base 174 during movement of the carriage longitudinally thereof. This means comprises a plate 216 which is mounted in the carriage portion 168 for movement transversely of the base 174 and which includes laterally extending edge portions 218 received in complementary grooves extending transversely of the carriage portion 168 for preventing vertical or pivotal movement of the plate 216 relative to the carriage portion 168. The drill positioning assembly 170 is secured to the plate 216 by means of screws 220 extending through the plate 216 and threaded into the block member 194.

The position of the drill positioning means 170 and the plate 216 upon which it is mounted, transversely of the base 174, is at all times controlled by the cam surface 180 formed on the workpiece supporting plate 172, which cam surface 180 is continuously engaged by a roller 222 mounted on the inner face of the block member 194. The plate 216 is urged inwardly at all times during the drilling operation to hold the roller 222 against the cam 180 by a suitable hydraulic cylinder and piston motor 224 which is anchored to a laterally outwardly extending arm 226 mounted on the carriage portion 168 and which acts against the plate 216 to continuously urge it inwardly or to the left as viewed in Fig. 10.

In the machine 160 only one carriage connector rod 227, corresponding to the rod 78 of the machine 20, is required, due to the elimination of the carriage portion 66.

It will be appreciated that during operation of the above described machine 160 the drill is actually distorted to follow the curve along which the projecting portions 164 are disposed during each drilling operation. To insure the proper positioning of the cutting end of the drill during its entry into each of the workpiece projecting portions 164, a locating finger 228 is mounted on the inner end of the drill positioning member 200 and is adapted to engage the workpiece 162 adjacent the base of the projecting portions 164. This construction insures an accurate positioning of the drill and compensates for any slight inaccuracies which might result from the shaping of or positioning of the cam 180 on the supporting plate 172.

While only two specific embodiments of the invention have been illustrated and described herein, it will be readily appreciated by those skilled in the art that numerous modifications and changes may be made without departing from the spirit of the present invention.

What is claimed is:

1. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill,

70

75

and means mounted on said carriage for moving said elements into and out of said supporting engagement with said drill.

2. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill, means mounted on said carriage for moving said elements into and out of said supporting engagement with said drill, and cooperating means on said carriage and said base for automatically actuating said last named means during movement of said carriage along said base.

3. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill, and means mounted on said carriage for moving said elements into and out of said supporting engagement with said drill, said drill supporting elements being disposed to engage said drill adjacent the cutting end thereof.

4. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill, and means mounted on said carriage for moving said elements into and out of said supporting engagement with said drill, the spacing of said drill supporting elements relative to the end of said drill being so proportioned relative to the spacing between said projections on said workpiece that said elements may be moved into said supporting engagement with said drill to accurately position the cutting end of said drill during its entry into each of said projections on said workpiece.

5. A deep drilling machine for drilling an opening through a plurality of spaced projecting por-

tions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill, and means mounted on said carriage for moving said elements into and out of said supporting engagement with said drill, the spacing of said drill supporting elements relative to the end of said drill being so proportioned relative to the spacing between said projections on said workpiece that said elements may be moved into said supporting engagement with said drill to accurately position the cutting end of said drill during its entry into each of said projections on said workpiece, and cooperating means on said carriage and said base for automatically actuating said last named means whereby said elements are moved into said supporting engagement with said drill to accurately position the cutting end of the drill during its entry into each of said projections.

6. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill, and means mounted on said carriage for moving said elements into and out of said supporting engagement with said drill, the spacing of said drill supporting elements relative to the end of said drill being so proportioned relative to the spacing between said projections on said workpiece that said elements may be moved into said supporting engagement with said drill to accurately position the cutting end of said drill during its entry into each of said projections on said workpiece, and cooperating means on said carriage and said base for automatically actuating said last named means whereby said elements are moved into said supporting engagement with said drill to accurately position the cutting end of the drill during its entry into each of said projections and automatically retracting said elements to prevent interference between said elements and said projections during movement of said carriage along said base.

7. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base

to move said drill toward and through said workpiece, drill positioning means mounted on said carriage in spaced relation to said first named means and including drill supporting elements adapted to be moved between said spaced projecting portions of said workpiece to move into and out of supporting engagement with said drill, means mounted on said carriage for moving said elements into and out of said supporting engagement with said drill, and means mounted on said base and adapted to rotatably support said drill at a plurality of points along said base intermediate said workpiece and said first named means.

8. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill, means mounted on said carriage for moving said elements into and out of said supporting engagement with said drill, means mounted on said base and adapted to rotatably support said drill at a plurality of points along said base intermediate said workpiece and said first named means, and means for rendering said last named means inoperative at each of said plurality of points as it is approached by said first named means.

9. A deep drilling machine for drilling an opening through a plurality of spaced projecting portions of a workpiece such as a hinge or the like, said machine comprising a base, a carriage mounted on said base for movement therealong, means mounted on said carriage for mounting and rotating an elongated drill, means mounted on said base for holding a workpiece to be drilled, means for moving said carriage along said base to move said drill toward and through said workpiece, drill positioning means mounted on said carriage in spaced relation to said first named means and including drill supporting elements adapted to be moved between said spaced projecting portions of said workpiece to move into and out of supporting engagement with said drill, and means mounted on said carriage for moving said elements into and out of said supporting engagement with said drill, said last named means comprising resilient means urging said elements in one direction and selectively operable means adapted to move said elements in the opposite direction against the action of said resilient means.

10. A deep drilling machine for drilling an opening through a plurality of spaced projecting portions of a workpiece such as a hinge or the like, said machine comprising a base member, a carriage member mounted on said base member for movement therealong, means mounted on said carriage member for mounting and rotating an elongated drill, means mounted on said base member for holding a workpiece to be drilled, means for moving said carriage member along said base member to move said drill toward and through said workpiece, drill positioning means mounted on said carriage member in spaced relation to said first named means and including drill

supporting elements adapted to be moved between said spaced projecting portions of said workpiece to move into and out of supporting engagement with said drill, and means mounted on said carriage member for moving said elements into and out of said supporting engagement with said drill, said last named means comprising resilient means urging said elements in one direction into said supporting engagement with said drill and solenoid means adapted upon energization thereof to move said elements in the opposite direction.

11. A deep drilling machine for drilling an opening through a plurality of spaced projecting portions of a workpiece such as a hinge or the like, said machine comprising a base member, a carriage member mounted on said base member for movement therealong, means mounted on said carriage member for mounting and rotating an elongated drill, means mounted on said base member for holding a workpiece to be drilled, means for moving said carriage member along said base member to move said drill toward and through said workpiece, drill positioning means mounted on said carriage member in spaced relation to said first named means and including drill supporting elements adapted to be moved between said spaced projecting portions of said workpiece to move into and out of supporting engagement with said drill, means mounted on said carriage member for moving said elements into and out of said supporting engagement with said drill, said last named means comprising resilient means urging said elements in one direction into said supporting engagement with said drill and solenoid means adapted upon energization thereof to move said elements in the opposite direction, switch means mounted on one of said members, and cam means mounted on the other of said members and proportioned to actuate said switch means to withdraw said elements from engagement to prevent interference between said elements and said workpiece during movement of said carriage member along said base.

12. A deep drilling machine for drilling an opening through a plurality of spaced projecting portions of a workpiece, which portions are disposed along a gentle curve, said machine comprising a base, a carriage mounted on said base for movement therealong, means mounted on said carriage for mounting and rotating an elongated drill, means mounted on said base for holding said workpiece, means for moving said carriage longitudinally of said base to move said drill toward and through said workpiece, drill positioning means mounted on said carriage in spaced relation to said first named means and in-

cluding drill supporting members adapted to be moved between said spaced projecting portions of said workpiece to move into and out of supporting engagement with said drill and means mounted on said carriage for moving said members into and out of said supporting engagement with said drill, and cooperating means on said carriage and said base for moving said drill positioning means transversely of said base during movement of said carriage longitudinally thereof whereby said drill positioning means follows said curve along which said projecting portions of said workpiece are disposed.

13. A deep drilling machine for drilling an opening through a plurality of spaced projecting portions of a workpiece, which portions are disposed along a gentle curve, said machine comprising a base, a carriage mounted on said base for movement therealong, means mounted on said carriage for mounting and rotating an elongated drill, means mounted on said base for holding a said workpiece, means for moving said carriage longitudinally of said base to move said drill toward and through said workpiece, drill positioning means mounted on said carriage in spaced relation to said first named means and including drill supporting members adapted to be moved between said spaced projecting portions of said workpiece to move into and out of supporting engagement with said drill and means mounted on said carriage for moving said members into and out of said supporting engagement with said drill, and cooperating means on said carriage and said base for moving said drill positioning means transversely of said base during movement of said carriage longitudinally thereof whereby said drill positioning means follows said curve along which said projecting portions of said workpiece are disposed, said last named means comprising cam means on said base, cam follower means on said drill positioning means, and means mounted on said carriage urging said cam follower means against said cam means.
